CLAIM

The ornamental design for a cart apparatus with a top support having a plurality of openings, as shown and described.

DESCRIPTION

FIG. 1 is a front perspective view of a cart apparatus with a top support having a plurality of openings according to the design with a door in an open position;

FIG. 2 is a front perspective view thereof with containers fully disposed through each of the plurality of openings and through an intermediate support;

FIG. 3 is a front perspective view thereof with the door in an alternative closed position and with a container partially disposed through one of the plurality of openings;

FIG. 4 is a front perspective view thereof with the door in an alternative closed position;

FIG. 5 is a front view thereof with the door in the alternative closed position of FIG. 4;

FIG. 6 is a rear view thereof with the door in the alternative closed position of FIG. 4;

FIG. 7 is a right side view thereof with the door in the alternative closed position of FIG. 4;

FIG. 8 is a left side view thereof with the door in the alternative closed position of FIG. 4;

FIG. 9 is a top view thereof with the door in the alternative closed position of FIG. 4; and,

FIG. 10 is a bottom view thereof with the door in the alternative closed position of FIG. 4.

The broken lines in the figures showing containers, a door knob, door trim, and wheels show environment and form no part of the claimed design.
